UNITED STATES PATENT OFFICE

114,412

DESIGN FOR A STANDARD FOR A SHOE MACHINE

Frederick A. Prahl, Jr., Danvers, Mass., assignor
to United Shoe Machinery Corporation, Pat-
erson, N. J., a corporation of New Jersey

Application December 31, 1938, Serial No. 82,098

Term of patent 14 years

To all whom it may concern:

Be it known that I, Frederick A. Prahl, Jr., a citizen of the United States, residing at Danvers, in the county of Essex and Commonwealth of Massachusetts, have invented a new, original, and ornamental Design for Standards for Shoe Machines, of which the following is a specification, reference being had to the accompanying drawing, forming part thereof.

The figure is a perspective view of a standard

for a shoe machine embodying my new design.

The side of the standard which does not appear in the drawing is substantially like the side shown.

I claim:

The ornamental design for a standard for a shoe machine, substantially as shown and described.

FREDERICK A. PRAHL, JR.
